UNITED STATES PATENT OFFICE.

JAMES S. MILLER, OF CLINTON, NEBRASKA.

RAILWAY-TIE.

SPECIFICATION forming part of Letters Patent No. 727,403, dated May 5, 1903.
Application filed December 12, 1902. Serial No. 134,943. (No model.)*To all whom it may concern:*

Be it known that I, JAMES S. MILLER, a citizen of the United States, and a resident of Clinton, in the county of Sheridan and State of Nebraska, have invented a new and Improved Railway-Tie, of which the following is a full, clear, and exact description.

This invention relates to improvements in railway-ties, the object being to provide a tie, consisting partly of wood and partly of metal, so constructed that the rails will be prevented from spreading and will rest on the wood portions, thus obtaining the requisite elasticity.

15 I will describe a railway-tie embodying my invention and then point out the novel features in the appended claims.

Reference is to be had to the accompanying drawings, forming a part of this specification, 20 in which similar characters of reference indicate corresponding parts in all the figures.

Figure 1 is a perspective view showing railway-ties embodying my invention as applied. Fig. 2 is a plan view of one of the ties. Fig. 25 3 is a section on the line 3 3 of Fig. 2. Fig. 4 is a section on the line 4 4 of Fig. 2, and Fig. 5 is a section on the line 5 5 of Fig. 4.

The tie consists of a casing 10, formed of steel or other suitable metal, and near the 30 ends of the casing openings 11 are formed, into which the bases of the rails pass and rest upon wooden blocks 12. These wooden blocks are preferably treated with creosote, crude oil, or other material which will increase the life of the blocks. By resting the 35 rails directly on the wooden blocks all the elasticity of the ordinary wooden tie is secured. The material cut out to form the opening 11 is turned into hook form 13 at one 40 side to engage the base of the rail at the inner side. At the opposite side the material is turned over, as indicated at 14, which forms a double thickness and stay portion, and in this turned-over part is a notch 15, 45 through which a spike 16 may pass. At the ends of the opening 11 the sides of the casing are cut down and the material is turned outward to form lips 17. By forming these lips below the plane of the top of the casing the 50 bearing of the rail upon the wood is insured.

When the block becomes worn, it may be forced farther inward to form a new bearing or it may be turned over.

The tie embodying my invention will be comparatively cheap to manufacture, and it 55 will prevent spreading or lateral tilting of the rails even on sharp curves.

Having thus described my invention, I claim as new and desire to secure by Letters Patent—

1. A railway-tie, comprising a metal casing having openings through its top wall, the material at one side of the openings being turned to form a hook adapted to engage with the base of the rail, and the material at the 65 opposite side being overlapped and provided with a notch, and blocks of wood arranged in the ends of the casing, substantially as specified.

2. A railway-tie, consisting of a metal casing having openings near its ends, the material of the casing at one side of the openings being curved to form hooks adapted to engage with the base of the rail, the material at the opposite side being overlapped and 75 provided with a notch, portions of the casing at the ends of the openings being cut downward at the sides and turned outward to form lips, and wooden blocks in the casing, upon which the rails may rest, substantially as 80 specified.

3. A railway-tie comprising a metal casing having openings through its top wall, the material of the casing at one side of the openings being curved to form hooks adapted to 85 engage with the base of a rail, the material at the opposite side being provided with a notch, the portions of the casing at the ends of the openings being cut downward at the sides and turned outward to form lips, and 90 wooden blocks in the casing upon which the rails may rest, substantially as specified.

In testimony whereof I have signed my name to this specification in the presence of two subscribing witnesses.

JAMES S. MILLER.
